UNITED STATES PATENT OFFICE.

EDWARD J. YETTER, OF DENVER, COLORADO.

SHEET-ROOFING.

1,398,250.

Specification of Letters Patent. Patented Nov. 29, 1921.

Application filed May 9, 1921. Serial No. 468,037.

To all whom it may concern:

Be it known that I, EDWARD J. YETTER, a citizen of the United States of America, residing at the city and county of Denver 5 and State of Colorado, have invented a new and useful Sheet-Roofing, of which the following is a specification.

My invention relates to a new type of flexible asphaltum shingle-appearing sheet 10 roofing.

And the objects of my invention are:

First, to provide individual sheets or strips of asphaltum roofing material of a width corresponding to the length of an 15 ordinary wooden shingle, their weather exposed surface being provided with raised rib members that are spaced at distances apart corresponding to the general width of individual wooden shingles, which ribs are 20 positioned along the length of the sheets of asphaltum thus giving to the sheets the appearance of wooden shingles.

Second, to provide long, narrow sheets or strips of asphaltum roofing material that 25 represent shingles, which shingle representing sheets may be of any predetermined length, and which shingle representing sheets or strips are manufactured and shipped in rolls of shingle length, and 30 which rolls are arranged to be laid in successive shingle laying and overlapping form, arranged and adapted to the same weather exposure and underlapping surfaces as is used with wooden shingles.

Third, to provide a simple and quick laying type of sheet asphaltum roofing which forms a continuous row of individually appearing shingled roofing that presents to the eye of observers when laid the appearance of 40 a wooden shingled roof.

I attain these objects by the form of roofing illustrated in the accompanying drawings in which:

Figure 1 is a perspective view of a portion 45 of a shingle-appearing strip constructed in accordance with my invention.

Fig. 2 is a view illustrating the manner of applying the shingle strips to the roof of a house.

Fig. 3 is an edge view of two overlapping shingle strips.

Fig. 4 is an enlarged sectional view on the line 4-4 of Fig. 1.

Fig. 5 is an enlarged perspective view,

showing a portion of a strip having relatively wide ribs, and

Fig. 6 is a view of a fragment of a strip showing the narrow form of rib.

Similar letters of reference refer to similar parts throughout the several views.

Referring to the drawings, the numeral 1, designates a sheet or a strip of my flexible asphaltum shingle representing roof sheeting material, which may be especially made up in the exact lengths required for the roof 65 it is to be laid on, or the strips may be cut from a long roll of the shingle sheeting.

Each sheet or strip 1, of my shingle representing roofing is preferably made nine inches wide and it contains at intervals of 70 preferably eight inches apart throughout its entire length a raised rib member 2, which varies in width from about one-fourth of an inch to about three-quarters of an inch in width, the wider rib members being more 75 easily seen on high buildings, while the narrower ribs are of ample width for low and medium height buildings. These raised rib members extend from the lower edge 3, of the shingle sheeting across its width for a 80 distance of preferably four inches, which distance is the preferred width of the weather exposed surface 4, of the strip of shingle representing roof sheeting.

As my continuous shingle representing 85 strips of roofing are nine inches wide and as four inches of it is exposed to the weather, the remaining five inches represents the underlapping portion 5, of the shingle strip, and of this five inches about one inch forms an 90 underlapping edge 6, which lies against the roof boards 7, and is overlapped five inches by the second shingle strip 1^A, above it, as shown at 8, in Fig. 2, and is overlapped about one inch by the lower end 9, of the 95 third shingle strip 1^B, above it, and my continuous shingle representing strips of flexible asphaltum are laid in this progressive overlapping order from the lower edge of a roof to its upper edge which arrangement 100 forms a three-ply thickness or three layers of the shingle representing roofing strips along the upper edge portion 12, of the weather exposed part of each shingle member and along each longitudinally extending 105 layer of the roof sheeting strips across the roof of a building.

The upper underlapping five inch portion

5, of each shingle representing strips 1, of roof sheeting, is provided with raised rib members 2^A, the same as the lower four inch weather exposed portion 4, and the raised 5 ribs 2^A of the underlapping portion 5, of the long shingle strip 1, are all also positioned at eight inches apart, by which is meant that they are eight inches apart from center to center of the ribs, which is also the distance 10 apart of the lower ribs 2, on the lower weather exposed portion 4, of the shingle strips. These raised members are designed to represent to the eye the cracks or narrow spaces that occur between wooden shingles 15 when laid, and also that become more pronounced through shrinkage of the wooden shingles after they are laid.

My invention contemplates any way of representing on the surface of the shingle 20 strips 1, of my asphaltum roofing material, such form and shape and character of raised rib members spaced at what is considered standard width of wood shingles that will represent to the eye of an observer from the 25 street, a roof that has been shingled with individual shingles, and I have represented both a wide rib 2, in Fig. 5, and a narrow rib 2^B, in Fig. 6.

My invention contemplates shingle representing ribs of any width, and they are formed by subjecting the strips of asphaltum to a rolling pressure, which is applied by feeding the strips through suitably formed rolls which forces the ribs outwardly from 30 the weather exposed side of these shingle wide strips into a narrow rib-like portion of the asphaltum, which pressed out rib-members project preferably about an eighth of an inch above the surface of all of the rest 35 of the width and length of these shingle strips of asphaltum roofing material, which is rolled out flat and smooth and of even thickness throughout their entire length and width except where their raised ribs are 40 formed.

In pressing out and thus projecting outwardly these ribs from the surface of the shingle forming strips 1, a recess 10, of corresponding depth and width is formed in 50 the under side surfaces of each rib exactly opposite to them as these ribs are formed by a swaging pressure movement that forces a raised rib shaped member of the shingle strip bodily at right angles to the underside 55 surface 11, of the shingle sheets, which forms the recess and at the same time forms the raised or projecting rib 2, on the upper or weather exposed surface of the shingle sheets.

60 The ribs 2^A, on the underlapping or upper side edge 5, of the shingle strips, and also their corresponding opposite side recesses are especially made shallower in height than the weather exposed ribs 2, on the lower 65 weather exposed part of the shingle strip,

and they are positioned centrally between the ribs 2, of the weather exposed lower part of the shingle strips, and they extend from the upper edge 12, of the shingle strips, down to even with the upper ends of the lower ribs 2, which is defined by a dotted line 13, and these upper shallow depth ribs have been especially designed to act as guide ribs to enable the shingle laying workman to plainly see that each shingle strip must be laid so that these shallower ribs will stand centrally between the ribs 2, on the same strip and in line with the ribs 2 on the shingle below; that is, that they will lay and extend upward from the center of the eight 70 inch space between the lower ribs in centrally positioned offset and alternate order of arrangement; and in laying the shingle strips the lower edges of each strip laid is placed with its lower edge throughout its length 80 across the length of the roll close up against the upper ends of the lower ribs 2, which would be along the dotted line 13, as the upper ends of the ribs 2, form a guide line 85 across the roof that the lower edge of each shingle strip that is to be laid on the one already laid is to be placed against, and when this is done the recesses in the under side of the lower portion of each shingle sheet as it is laid fits down over the shallower ribs 2^A, of the upper part 5, of the shingle strip that has been already laid on the roof.

The operation of laying my improved long, thin and flexible strips of shingle representing flexible asphaltum roofing material on pitch or inclined roofs is as follows and is as illustrated in Fig. 2:

A strip of the shingle representing roofing asphaltum is laid either fully across a roof lengthwise of it or as far across as desired at its lower or eaves edge, and is nailed to the roof boards; but the lower edge of this first shingle strip is bent down over the eaves board 3^A, and is extended far enough below its lower edge to form a water dripping edge, and this overlapping edge of this lower or first strip is then nailed to the eaves strip 3^A. A second sheet is then laid flatwise also along the length of the roof parallel to the first strip and overlapping the upper edge portion of it five inches; the workman adjusting the lower edge of the second to lay against the upper edges of the raised ribs 2, of the first shingle strip 105 laterally so that the ribs recesses on its under side will fit over the shallow ribs on the upper portion of the first and lower strip that has been nailed to the roof, which allows the flat under side surface of the upper 110 part of the second shingle strip to lie flat down against the lower shingle strip below it, and as it is soft and flexible it is easily pressed down perfectly flat and 115 smooth over the upper part of the strip un- 120 125 130

derneath by the workman, who then nails it tightly to the shingle strip below it. A third shingle strip is then laid to overlap the upper part of the second shingle strip 5 and is nailed to it and to the roof, as shown, and the lower edge portion of the third shingle strip can be nailed to the second shingle strip and also the one inch wide upper edge portion 6, of the first shingle laid 10 on the roof which projects up under about an inch of the lower edge of the third shingle strip, consequently there are three thicknesses of the shingle strips along the whole length of the roof at this triple overlapping 15 portion of them. The shingle strips are then laid in successive order to the ridge of the roof across its width or height.

My invention provides a thoroughly practical, durable and quickly and cheaply laid shingle representing roofing of an asphaltum composition that has been in constant use for roofings for buildings of all kinds for a good many years, a practical application of which was invented and patented by 25 me in Patent No. 1,148,647, issued August 3, 1915.

Having described my invention what I claim as new and desire to secure by Letters Patent is:

30 1. A shingle representing strip of roofing material made of the width of the length of shingles and provided with raised rib members on its weather exposed side positioned in offset centrally spaced order in 35 two rows along the length of said strip and arranged to define the outlines of separately laid shingles having an exposed surface of standard width.

2. A shingle representing strip of roofing 40 material made of the width of the length of shingles and provided with raised rib members on its weather exposed side positioned in offset centrally spaced order in two rows along the length of said strip and arranged 45 to define the outlines of separately laid shingles having an exposed surface of standard width; the lower row of said ribs being adapted to be exposed to the weather with the lower portion of said strip and the upper 50 per row being formed to act as a guide in placing another shingle strip over the lower one in shingle laying order.

3. A shingle representing strip of roofing material made of the width of the length of 55 shingles and provided with raised rib members on its weather exposed side positioned in offset centrally spaced order in two rows along the length of said strip and arranged to define the outlines of separately laid shingles 60 having an exposed surface of standard width; the lower row of said ribs being adapted to be exposed to the weather with the lower portion of said strip and the upper row being adapted to act as a guide in placing another shingle strip over the lower one 65

in shingle laying order; said shingle strip being the width of the standard length of wooden shingles and said strips being so arranged that one strip is laid on the upper part of another and with its lower edge 70 against the upper ends of the lower row of ribs of the weather exposed surface of said strip.

4. A shingle representing strip of roofing material made of the width of the length of shingles and provided with raised rib members on its weather exposed side positioned in offset centrally spaced order in two rows along the length of said strip and arranged to define the outlines of separately laid shingles having an exposed surface of standard width; the lower row of said ribs being adapted to be exposed to the weather with the lower portion of said strip and the upper row being adapted to act as a guide in placing another shingle strip over the lower one in shingle laying order; said shingle strip being the width of the standard length of wooden shingles and said strips being so arranged that one strip is laid on the upper 75 part of another and with its lower edge 80 against the upper ends of the lower row of ribs of the weather exposed surface of said strip; said overlapping shingle appearing strip being provided on its under side with a recess corresponding to the width and length of the rib members on its upper or weather exposed side, whereby when one strip is laid on top of another it is positioned 85 so that its recesses fit over the raised ribs 90 on the strip below it.

5. A shingle representing strip of roofing material made of the width of the length of shingles and provided with raised rib members on its weather exposed side positioned in offset centrally spaced order in two rows along the length of said strip and arranged to define the outlines of separately laid shingles having an exposed surface of standard width; the raised ribs on the upper portion 105 of said strip being made of less height than the raised ribs on the exposed surface of said strip.

6. A shingle representing strip of roofing material made of the width of the length of shingles and provided with raised rib members on its weather exposed side positioned in offset centrally spaced order in two rows along the length of said strip and arranged to define the outlines of separately laid shingles having an exposed surface of standard width; the lower row of said ribs being adapted to be exposed to the weather with the lower portion of said strip and the upper 110 row being adapted to act as a guide in placing another shingle strip over the lower one in shingle laying order; said shallower ribs on the upper portion of said strip extending from the upper edge of said strip to the upper ends of said weather exposed ribs. 115 120 125 130

7. A shingle representing strip of roofing material formed into a weather exposed portion and an underlapping portion to another similar shingle representing strip, said strip being made of a width equal to the standard length of shingles and having two rows of offset centrally and equally spaced raised rib members on its weather exposed surface placed at a distance apart equal to 10 the standard width of shingles and arranged and adapted to appear as the spaces between shingles, the raised ribs on the underlapping portion of said shingle representing strip being made of shallower depth than those of 15 the weather exposed portion and being ar-

ranged and adapted to form guide ribs, said strip being formed with recesses on its under side corresponding to the height and width of the raised rib members on its weather exposed side, said recesses being arranged to fit over said guide ribs when, one shingle strip is laid in shingle laying relation over another. 26

In testimony whereof I affix my signature in presence of two witnesses.
